UNITED STATES PATENT OFFICE.

HENRY C. SWAN, OF OSHKOSH, WISCONSIN.

KING-BOLT SOCKET.

SPECIFICATION forming part of Letters Patent No. 653,269, dated July 10, 1900.

Application filed May 12, 1900. Serial No. 16,453. (No model.)

To all whom it may concern:

Be it known that I, HENRY C. SWAN, a citizen of the United States of America, residing at Oshkosh, Winnebago county, Wisconsin, have invented certain new and useful Improvements in King-Bolt Sockets, of which the following is a specification in such full, clear, and exact terms as to enable any person skilled in the art to which it appertains to make, construct, and use the same.

My invention relates to improvements in king-bolt sockets for vehicles, and has for its object to provide a king-bolt that can be secured to axles of varying depths without adjustment of any of the parts forming the king-bolt socket.

In the accompanying drawings, Figure 1 is a plan view of a fifth-wheel provided with my improved king-bolt socket. Fig. 2 is a longitudinal section of the same on the line 2 2 of Fig. 1. Fig. 3 is a transverse section on the line 3 3 of Fig. 1. Fig. 4 is a plan view of the clip-tie. Fig. 5 is a side elevation of the same.

The socket for the king-bolt 1 consists of 25 perforated collars 2, formed integral with the bolster-plate 3, that is secured to the bolster 4, a collar 5, preferably formed integral with the brace 6, a sleeve 7, formed with the lower fifth-wheel 8, and a collar 9, provided upon the end 30 of the lower perch-irons 10. A clip 11 fits over the axle opposite said king-bolt socket and is secured by a clip-tie 12, which is provided with a perforated collar 13, that encircles the king-bolt socket and is movable longitudinally thereon. The clip-tie is preferably constructed with its collar offset, as at 14, so as to arrange the same above the lower perch-irons in case an axle of unusual depth is used.

By means of this construction I am enabled

to provide a king-bolt socket that may be used 40 with axles of varying depths without readjustment of any of the parts forming said socket, since the same is secured to the bottom of the axle by means of the tie-clip, which is adjustable longitudinally of the socket. Heretofore 45 it has been customary to construct the king-bolt socket so that the collar on the clip-tie would form a part thereof, which prevented longitudinal adjustment of the clip-tie and required the axle to be of a fixed depth to allow 50 the parts to fit properly.

By my construction the depth of the axle is immaterial, since the collar upon the clip-tie can be moved without disturbing or interfering in any way with the parts forming the 55 king-bolt socket, and at the same time said socket is securely held in its proper relative position to the axle.

I claim as my invention—

1. The combination with a king-bolt socket, 60 of a clip-tie rigidly secured to the axle and provided with the collar encircling the king-bolt socket and adjustable longitudinally thereof, substantially as described.

2. The combination with a sleeve rigidly 65 secured to the lower fifth-wheel and forming a part of the king-bolt socket, of a clip-tie provided with a collar offset from said clip-tie encircling said sleeve and movable longitudinally thereof, substantially as described. 70

In witness whereof I sign this application, in the presence of two witnesses, this 5th day of May, 1900.

HENRY C. SWAN.

Witnesses:

S. D. SANOR,
C. I. HENDERSON.
